(57) **CLAIM**

The ornamental design for an unmanned aerial vehicle, as shown and described.

DESCRIPTION

FIG. 1 is a perspective view of an unmanned aerial vehicle embodying the new design;

FIG. 2 is a side view thereof;

FIG. 3 is another side view thereof;

FIG. 4 is a back view thereof;

FIG. 5 is a front view thereof;

FIG. 6 is a top view thereof; and,

FIG. 7 is a bottom view thereof.

In the drawings, the broken lines depict portions of the unmanned aerial vehicle that form no part of the claimed design.
